UNITED STATES PATENT OFFICE.

BERNHARD VON FRANTZIUS, OF BERLIN, GERMANY.

HAT-FASTENER.

SPECIFICATION forming part of Letters Patent No. 741,024, dated October 13, 1903.

Application filed October 22, 1900. Serial No. 33,827. (No model.)

To all whom it may concern:

Be it known that I, BERNHARD VON FRANTZIUS, a subject of the King of Prussia, German Emperor, residing at the city of Berlin, in the 5 Kingdom of Prussia, Germany, have invented a certain new and useful Improvement in Hat-Fasteners, of which the following is a specification, such as will enable others skilled in the art to which it appertains to make and use 10 the same.

This invention relates to improvements in hat-fasteners; and it consists in a device by which the hats of women may be fastened upon the head in a very simple and secure 15 manner, the hats not being in danger of being injured, no part of the device being capable of being lost, and the same being incapable of inflicting wounds upon the user or others.

On the accompanying drawings, Figures 1 20 and 2 represent in vertical and horizontal section a hat provided with this fastener. Fig. 3 shows the head end of the securing-pin on an enlarged scale. Figs. 4, 5, 6, and 7 are various forms of pin-holding plates for the securing 25 end of the hat-pins, and Figs. 8 and 9 show a fastening-pin of single instead of doubled wire adapted to be used with my improved form of fastening or securing plate.

The hat-fastener consists of a securing-pin, 30 Figs. 1, 2, and 3, and devices for securing the same on the head and in the hat. The pin is usually composed of a piece of suitable resilient spring-wire bent upon itself into the form of a hair-pin, pointed at one end and 35 screw-threaded at the other, (designated by the letter *a*,) and a head *b*, secured upon the two ends.

The head *b* is of any convenient form or 40 size and may be made of ebonite, ivory, celluloid, or any other convenient material and has two holes, the diameter of which being a little smaller than the wire of which the pin *a* is made. By screwing the threaded end *c* into one of them a screw-thread will be cut 45 in the hole. To secure the pin in the hat, the ends *d* and *c* are passed outward through the side of the hat from within, Figs. 1 and 2, at the proper point, and the head *b* is screwed on the threaded end *c*, after which the pointed 50 end *d* is bent so as to allow it to be placed in the hole provided for it in the head *b*, where

it will be held by the natural resiliency of the wire.

On the inner side of the hat, opposite to the point through which the pin *a* is passed, a 55 holder or securing-plate *f* (usually of the form shown in Fig. 4) is secured. This holder or securing-plate *f* is made of metal, ebonite, or the like, is usually of oblong shape, and is provided with means for securing the loop 60 end of the pin *a* thereto, which in this case consists of cross-bars *g*, provided with comb-like points or teeth *h*, Fig. 4, over any of which the loop of the pin will fit, so as to secure the pin against withdrawal. Sometimes 65 the plate *f* instead of being provided with teeth is in the form of a grating formed of resilient spring-wires, as shown in Figs. 5 and 6, in which case the doubled end of the wire forming the pin *a* is forced between such wires 70 after being passed through the hair of the wearer and is there held by the resiliency of such plate-wires. In other cases the securing-plate may be composed of close-woven wire fabric or netting, as shown in Fig. 7, and in 75 such case a pin having a single wire and with a grooved and pointed or enlarged and pointed or enlarged pointed screw-threaded end, as shown in Figs. 8 and 9, may be used, the point being screwed or driven into the fine 80 mesh of the metallic fabric and there held. In any event the plate *f* is secured to the hat in any desired manner, usually by being sewed thereto, it being for that purpose usually provided with holes at two or more of the 85 edges, as shown. If desired, the pins may be used without a securing-plate, and when two are so used they will secure the hat in position against all save the highest of winds.

Having now fully described my said invention, what I claim, and desire to secure by Letters Patent, is—

1. A pin comprising a resilient wire looped upon itself and pointed at the ends, one only of such ends being provided with a screw-thread, and a head provided with a perforation into which the threaded end may be screwed, and a second perforation into which the other end may be slipped and thereafter held therein by the natural resiliency of the 95 wire, substantially as shown and described.

2. A hat-securing device comprising a se- 100

curing-plate having a plurality of teeth, and a hat-pin provided with an end loop adapted to slip over any one of the teeth of the securing-plate, substantially as shown and described.

3. In a hat-fastener the combination with a head portion, of a pin portion, consisting of two members forming a loop, one member being connected to the head portion and the other member being adapted to removably engage a suitable recess in the head portion of the fastener, whereby the fastener may be readily applied and securely attached to a hat and easily removed therefrom, substantially as described.

4. In a hat-fastener the combination with a head portion, of a pin portion consisting

of two members forming a loop, one member being connected to the head portion and the other member having a pointed end adapted to form an opening in and pass directly through the hat and removably engage a suitable recess in the head portion of the fastener, whereby the fastener may be readily applied and securely attached to a hat and easily removed therefrom, substantially as described.

In testimony that I claim the foregoing as my invention I have signed my name in presence of two subscribing witnesses.

BERNHARD VON FRANTZIUS.
